Primary Examiner — Paula Allen Greene*(74) Attorney, Agent, or Firm* — ScienBiziP, P.C.(57) **CLAIM**

The ornamental design for a pet cremation urn box, as shown and described.

DESCRIPTION

FIG. 1 is a front, right, and top perspective view of a pet cremation urn box, showing my design.

FIG. 2 is a rear, left, and bottom perspective view thereof.

FIG. 3 is a front elevation view thereof.

FIG. 4 is a rear elevation view thereof.

FIG. 5 is a left side elevation view thereof.

FIG. 6 is a right side elevation view thereof.

FIG. 7 is a top plan view thereof.

FIG. 8 is a bottom plan view thereof; and,

FIG. 9 is another, front, right, and top perspective view of FIG. 1 with the lid in an opened position thereof.

The broken lines shown in the drawings are included for the purpose of illustrating portions of the pet cremation urn box that form no part of the claimed design.
